UNITED STATES PATENT OFFICE.

RUFUS H. SHUMWAY AND WILLIAM D. SHUMWAY, OF LEBANON SPRINGS,
NEW YORK, ASSIGNEES TO SAID RUFUS H. SHUMWAY.

SAW-HANDLE.

SPECIFICATION forming part of Letters Patent No. 300,907, dated June 24, 1884.

Application filed March 24, 1884. (Model.)

To all whom it may concern:

Be it known that we, RUFUS H. SHUMWAY and WILLIAM D. SHUMWAY, both of Lebanon Springs, in the county of Columbia and State 5 of New York, have invented certain new and useful Improvements in Saw-Handles, of which the following is a full, clear, and exact description.

This invention more particularly relates to 10 the handles of cross-cut saws for sawing logs and trees; and it consists in the construction and arrangement of parts, as will be herein-after fully described and claimed.

Reference is to be had to the accompanying 15 drawings, forming a part of this specification, in which similar letters of reference indicate corresponding parts in all the figures.

Figure 1 represents a side view of a cross-cut saw-blade in part, with one of its handles, 20 and as in position for sawing up logs, the means used for attaching the saw-blade being the same as regards both end handles. Fig. 2 is an inside face view of the handle with the saw-blade detached; Fig. 3, a section on 25 the line xx in Fig. 1; and Fig. 4, a side view of the handle with the saw-blade adjusted into a plane at right angles to the position shown for it in Fig. 1, and adapted to sawing trees.

A indicates one handle of the saw, which is 30 grooved longitudinally and crosswise on the inner end of its face, to receive on and within it plates B B and C C, constructed and arranged to form longitudinal grooves $b b$ and cross-grooves $c c$, of any desired depth and of 35 a width corresponding with the thickness of the saw-blade or thereabout, so as to receive the end of the saw-blade freely within them.

The wood portion of the handle is also constructed with a many-sided rectangular recess, d , extending inward from its front side or face at the junction of the plates B B and C C, and said plates constructed to correspond, the same forming rectangular spaces or cavities $e f$ at right angles with each other and respectively parallel with the grooves $b c$. The handle A has also a hole, g , through it in line

with the junction of said plates, and may be fitted with a perforated back plate, D.

E is a hook, the body h of which is of flattened construction and set to one side of the screw-shank i , and the nose k of which is arranged to engage with a hole, l , near the end of the saw-blade G when in place.

To secure the saw-blade in position for sawing up logs, as shown in Figs. 1 and 3, the blade G, having the nose k of the hook inserted through the hole l in it, is adjusted into a vertical position with its teeth downward, and is inserted at both of its ends, respectively, within the longitudinal grooves b in either handle, and the body and shank portion of the hook projected within and through the handle, and so that the flattened portion h of the hook engages with the walls of the rectangular space 65 or cavity e , to lock the saw-blade in position, a thumb-screw, H, being applied to the screw-shank of the hook to tighten the saw-blade in its place.

When it is required to secure the saw-blade 70 in position for sawing trees, said blade is adjusted to lie horizontally or crosswise of the handle or handles, as shown in Fig. 4, and the flattened portion h of the body of the hook made to engage with the walls of the rectangular locking space or cavity f , and the thumb-nut H turned to tighten up the saw-blade, as 75 before.

Having thus described our invention, we claim as new and desire to secure by Letters 80 Patent—

The combination, with either saw-handle A, of the plates B C, constructed to form longitudinal grooves b , cross-grooves c , and locking-cavities $e f$, the saw-blade-holding hook 85 E, constructed to engage with the walls of either of said cavities, and the nut H, essentially as shown and described.

RUFUS H. SHUMWAY.

WILLIAM D. SHUMWAY.
